UNITED STATES PATENT OFFICE.

GEORGE H. MAAS, OF MILWAUKEE, WISCONSIN, ASSIGNOR OF ONE-HALF TO SARAH KARGER, OF MILWAUKEE, WISCONSIN.

SAFETY FEEDING DEVICE FOR COMPRESSION ROLLS.

Application filed November 7, 1921. Serial No. 513,318.

My invention relates to a new and improved feeding device for use in connection with compression rollers for any purpose, so that materials may be fed manually to such rollers, as heretofore, without liability to injury to the fingers or hands of the operator of the machine.

In prior structures of this type, the actual initial feeding of the materials to the rollers usually has been effected by the hands of the operator, and in frequent instances such practice has resulted in serious, permanent injury to the operator, whose fingers have been caught between the compression rollers and badly crushed. In other cases, the hand of the operator, and even the arm, has been drawn between the rollers and the injury inflicted, before the movement of the rollers could be arrested.

The present invention has been devised with a view to eliminating the dangers attendant upon the use of the older forms of machines, and in achieving that very desirable result, I have produced a device which feeds material to the rollers as efficiently as could be done by the fingers of the operator, and with absolute safety and freedom from liability to injury.

In its mechanical construction, my improvement has been embodied in a device which is intended to serve as an adjunct to an ordinary set of compression rollers, and which while feeding the materials initially to the rollers, will act at the same time as a guard to close the space forming the entrance between the rollers, and thus effectually prevent the fingers of the operator from being placed in such proximity to the rollers as to incur any liability to injury.

The adjunctive device may be termed a carrier, upon which the materials to be fed to the rollers are placed by the operator. The carrier is then moved into operative relation to the rollers, which latter in their rotation grip and draw the materials from the carrier and through or between the rollers in the continued rotation of the latter. As before indicated, the movement of the carrier to a position where it feeds the materials supported thereby to the rollers, closes the entrance to the rollers so that the fingers of the operator cannot by any possibility be drawn between the rollers.

In its broader aspects, my invention comprises a carrier, conveniently formed as a

pivoted bar or otherwise, on which are placed the materials to be fed between the compression rollers, and adapted to be moved into an operative position contiguous to the rollers, so that when in such operative relation to the rollers by their rotation will draw the materials from the carrier, which latter may then be retracted preparatory to another feeding operation.

In the drawing, I have illustrated the invention as an adjunct to a laundry wringer of common type, and while this instances the present contemplated use of the invention, it is to be understood that the invention is not to be so limited in its use, but that it possesses adaptability for use in relations other than those shown as well as for purposes other than those stated.

The novel features of the invention will be pointed out in the claims appended hereto.

In the drawing,

Figure 1 is a view in front elevation of a clothes wringer of common type, having my invention in one of its forms applied thereto.

Fig. 2 is a view looking from the top of Fig. 1, and showing the relative arrangement of the invention to the frame of the wringer, the top bar of the latter being shown in dotted lines.

Fig. 3 is an enlarged vertical sectional view on the line 3—3, Fig. 2, looking in the direction of the arrow, and showing my invention in feeding relation to the compression rollers of the wringer.

Fig. 4 is a view from the right of Fig. 3, showing certain details of construction of the invention.

Fig. 5 is a perspective view of the hanger or bracket by means of which the device is connected to the frame of the wringer.

Fig. 6 is a view similar to Fig. 3, and showing a modification of the construction of the feeding and safety device.

Referring to the drawing, the numeral 10 indicates the frame of a clothes wringer of ordinary type, designed for domestic use in which frame a pair of compression rollers 11 and 12 respectively are journaled, and operated in the usual manner. The top roll 11 with capacity for vertical movement, is pressed into engagement with the bottom roll 12 by the action of a bow spring 13.

A wringer having the construction thus described presents no features of novelty. In use, it is customary for the laundress to

enter the laundry work between the revolving rollers. At such times the rollers do not always pick up the work readily, and the feeding movement is augmented by the pressure of the fingers of the laundress in an effort to initiate the feeding of the material between the rollers. It frequently happens that the fingers of the operator are drawn between the revolving rollers and injured, 10 sometimes quite badly, before the rotation of the rollers can be arrested. Industrious workers are more often subjected to injury in this way.

In order to eliminate the liability to the 15 incurrence of injuries in the manner described, I have devised an adjunctive means for effecting the feeding of the work to the wringer, and I do this with my invention with greater facility than the wringer can be 20 fed by hand. In my invention the dangers heretofore existing are entirely obviated.

In the form in which I have chosen to illustrate my invention, I form a bracket 14 having laterally projecting ears 15 formed 25 thereon, and provided with aligned openings 16. The said bracket is conveniently attached to one of the uprights of the wringer frame. My feeding device comprises a horizontally extending bar 17, provided at one end with an angularly extending pin 18, which is adapted to be seated in the openings 16 of the bracket, so that the bar 17 may be swung upon its pivot point toward and away from the rollers and in 30 the horizontal plane of the space between the same. The bar 17 is provided on its inner face with a narrowed projection in the form of a longitudinal rib 19, which when the bar is swung forward is adapted to enter closely the space formed by the convergence of the surfaces of the rollers, but restrained from contact therewith.

The projection 19 on the face of the bar 17 may be recessed for the reception of a 45 plurality of balls 20, mounted to rotate upon axes 21 fixed in the projection upon the bar, as shown in Figs. 1 to 4.

In operation, the bar 17 will be swung upon its pivotal support away from the 50 wringer, as indicated by the dotted arrow in Fig. 2, and the wet fabric 22 or other article from which the moisture is to be expelled will be laid over the bar as indicated in Fig. 3. The bar 17 will then be swung to its 55 position in proximity to the rollers 11 and 12, sufficient pressure being applied to the bar to cause the surfaces of the balls 20 to have a frictional engagement through the fabric with the rolls of the wringer, and to 60 partake of a movement of rotation corresponding to that of the said rolls. This action serves to feed the fabric or other article into the narrow space formed by the convergence of the rollers 11 and 12, with the 65 result that the fabric is gripped and drawn

between the rollers. As soon as the fabric 22 or other article begins its feeding movement, the bar 17 may be swung away from the wringer, and the fabric will be drawn through the rollers by the continued rotation thereof.

In Fig. 6 I have shown a modified form of my invention which I find to have a practical efficiency. In such modified construction, the rotating balls are omitted, but the 75 device operates in the same manner as above described, inasmuch as the elongated rib 19, which is present in both constructions, serves to enter the fabric sufficiently into the narrow space between the rollers to enable the latter to grip the fabric and draw it between the wringer rollers 11 and 12. The vertical faces 23 of the bar shown in Fig. 6 act to limit the extent of the movement of the projecting rib 19 into the space 85 between the rollers.

The invention is applicable to both manually operated and power driven wringers. And while I have described the invention as applicable to a clothes wringer adapted 90 for laundry use, it is to be understood that my invention is not to be so limited in its use, but that it may be used in other relations and machines in which a similar feeding action takes place.

It will be noted that the bar 17 operates in the horizontal plane of the space between the rollers 11 and 12, and that when such bar is swung into its feeding position in proximity to the rollers, the space there between is effectually closed against the entry of the fingers of the operator.

Having thus described my invention, what I claim and desire to secure by Letters Patent of the United States, is:

1. A frame, a pair of compression rollers, a feeding member constituted as a bar pivoted at one end to the said frame to have a rotative movement toward the said rollers and adapted to insert the material to be compressed between the said rollers, said feeding member being provided with an extension adapted to enter the space formed by the convergence of the rollers to present the material to the grip of the rollers.

2. A frame, a pair of compression rollers, a feeding member constituted as a bar pivoted at one end to the said frame and adapted to be moved to insert the material to be compressed into the space formed by the convergence of the rollers to cause the latter to grip the material thus presented and draw it through the rollers.

3. A frame, a pair of compression rollers, a feeding member constituted as a bar pivoted at one end to the said frame and adapted to be moved to insert the material to be compressed between the rollers, said feeding member being provided at its front side with a projection penetrating the space between

the rollers and with means to limit the extent of such penetration.

4. A frame, a pair of parallel compression rollers, a bar pivoted to the frame in the plane between them and provided with a projection adapted to insert the material to be compressed between the rollers, said bar also being provided with rotatable means adapted to have frictional engagement with the material fed between the rollers and participate in the rotation of the latter.

5. A frame, a pair of parallel compression rollers, a feeding device comprising a bar pivoted at one end to the frame adjacent one journal of the said rollers and adapted to have a feeding movement into the space between the rollers, the said bar being provided with a rotatable element adapted to have frictional engagement with the material fed between the rollers and partake of the rotation of the latter.

6. The combination of a frame, parallel compression rollers, and a device for feeding material between the said rollers, the said

feeding device being constituted as a bar pivoted at one end to the frame and adapted to be turned on its pivot to carry the material into the space between the rollers, the said bar carrying a rotative element adapted to press the material against the rollers and participate in the rotation of the latter.

7. The combination of a frame, parallel compression rollers, and a device for feeding material between the said rollers, the said feeding device being constituted as a bar pivoted at one end to the frame and adapted to be turned on its pivot to carry the material toward the rollers, the said bar carrying on its face a projection adapted to enter the material between the rollers, and carrying also rotative elements for engaging the rollers to limit the movement of the said projection.

In testimony whereof, I have signed my name at Milwaukee, this 5th day of November, 1921.

GEO. H. MAAS.
